DIE HEAD

Charles A. Reimschissel, Waynesboro, Pa., assignor to Landis Machine Company, Waynesboro, Pa., a corporation of Pennsylvania

Application September 21, 1933, Serial No. 690,466

29 Claims. (Cl. 10—95)

This invention relates to threading die heads and particularly to such die heads as are used for cutting threads on bolts, screws, pipe, etc., using well known tangential end sharpened chasers.

5 The invention may be regarded in part as an improvement over the threading die head shown in the patent to Victor R. Koontz 1,456,805, dated May 29, 1923.

The object of the invention is to provide a 10 threading head of a simplified design which may be easily adjusted for thread of different size and which when locked in thread cutting position will be rigid so as to produce straight and accurate threads.

15 In the art of making screw threads there is an increasing demand for greater accuracy in the threads. One object of this invention is to provide a die head in which the thrust against the thread cutting elements is received against a rigid portion of the head so as to insure this high degree 20 of accuracy in the thread.

Further objects and advantages will become apparent from the description which follows:

25 Referring to the accompanying drawings which are made a part hereof and on which similar reference characters indicate similar parts,

Figure 1 is a face view of the threading head with one of the chaser holders removed,

Figure 2, a section on line 2—2 of Figure 1 with 30 the head in closed or locked position.

Figure 3 is a partial side elevation of Figure 1 showing the chaser holder seated in the head body and is a partial section on line 3—3 of Figure 1.

Figure 4 is a section on line 4—4 of Figure 2,

35 Figure 5, a rear end view of the threading head in locked or threading position.

Figure 6 is a side elevation partly in section of the head in open or non-threading position,

Figure 7, a partial side view showing the positions of the locking ring and the operating ring 40 when in open or non-threading position,

Figure 8, a side elevation partly in section of the head in locked or threading position.

Figure 9 a side elevation showing the locking 45 ring and the operating ring when the head is in locked or threading position.

In the drawings numeral 10 indicates the body member of the threading die head having chaser holders 11 carrying tangential chasers 12 which 50 chasers are secured in the holders by clamps 13 and clamp screws 14. The chaser holders may be those shown in the co-pending applications of C. A. Reimschissel No. 646,681, filed December 10, 1932 for Angular clamps and C. A. Reimschissel

and James G. Harper No. 646,932, filed December 12, 1932 for Chaser holders with heeled clamps.

The body member 10 is provided with slots 14' which form bearings in which the chaser holders 11 slide. These slots may be angular in shape as 5 shown or may be any desired shape such as a T-slot. The body member 10 has a flanged portion 16 provided with slots 15 extending therethrough which slots terminate in the slots 14' and form openings for operating prongs 17 formed on 10 a closing ring 20. The prongs 17 extend through the flange 16 and into slots 18 in the chaser holders 11. It will be noted that said slots 18 are open throughout their length into the peripheral surface of the chaser holder, whereby they may be 15 accurately ground for cooperation with prongs 17, and being open they facilitate in assembling and provide for compactness of the die head so that it may be made small in diameter which is a decided advantage where it is necessary to employ the die 20 head in close spaces. The slots 15 have sides 19 which are finished to serve as guides or keys for positioning the closing ring 20 on the body member 10. The flange 16 has a rearwardly extending portion 21 which telescopes over a flange 38 of an 25 operating ring 31 later to be described and forms a seal for preventing the entry of dirt into the working units of the head. The flange 16 and closing ring 20 are provided with sockets 22 and 30 respectively in which are seated springs 23 which serve to move the ring 20 rearwardly to open the die head. The body member 10 is provided with an extended portion 24 which serves for securing the die head to a rotatable support. The extended portion 24 is not necessarily cylindrical, as shown, but may be provided with a 35 flange or other standard means for attaching the die head to the operating spindle.

The body member 10 is threaded at 25 to receive a nut 26 which bears against a locking ring 27. 40 As will presently appear the nut 26 holds the locking ring 27 in correct axial position and also determines the operating position of the closing ring 20. By adjusting the nut 26 the extent of opening of the chasers is determined so that the head 45 may be adjusted for cutting thread of different diameters. The nut 26 may be secured in adjusted position by locking screw 53.

The locking ring 27 as best shown in Figures 50 6 and 8 is provided with abutments 28 which ride over abutments 29 on the rear of the closing ring 20 when the die head is in closed or locked position. The locking ring 27 is provided with two spiral grooves or cam surfaces 30. Pins 32 55

fixed in the operating ring 31 engage these grooves. When the die head is in closed or locked position, as shown in Figures 8 and 9, the pins 32 are positioned at the largest opening of the spiral as shown in Figure 9. When the operating ring 31 is moved rearward in relation to the face of the die head the pins 32 bear against the side of the spiral grooves 30 and rotate the locking ring 27 so that the abutments 28 and 29 may slip over each other into mating relation to permit the closing ring 20 to be moved to the rear by means of the springs 23. This moves the chasers to the open position. The prongs 17 on the closing ring 20 are provided with keyways 34 which engage over projections 35 in the angular slots 18 in the chaser holders 11. Keyways 34 and the projections 35 are parallel to the surface 36 as best shown in Figure 2. When the closing ring moves rearward therefore the chaser holders and the chasers are moved away from the work and at right angles to the axis of the work. The operating ring 31 may be moved rearward in relation to the face of the die head by any conventional means. The operating ring 31 is keyed to the closing ring 20 by means of a key 39 engaging the keyway 51 in the closing ring 20. The closing ring is positioned on the head body by means of the sides 19 of the irregular shaped slots 15 as stated above.

30 The key 39 prevents the operating ring 31 from rotating when the pins 32 ride against the sides of the spiral grooves 30 in the locking ring 27 when rotating the locking ring to unlocking position. When the operating ring 31 is moved forward toward the face of the die head it forces the closing ring 20 forward by contacting against a surface 40 on the closing ring. This action compresses the springs 23 and advances the closing ring far enough in the forward position to bring the abutments 28 out of sockets 41 in the rear of the closing ring. During a forward movement of the closing ring 17, the prongs force the chaser holder radially inward, the surfaces 36 at the bottom of slots 18 in chaser holders 11 being in engagement with correspondingly inclined surfaces 36a on the prongs 17,—an inward movement of the chaser holders is effected thereby. During a thread cutting operation these cooperating surfaces of the prongs and chaser holders bear the outward thrust.

50 This arrangement of the closing ring prongs 17 through the inclined cooperating surfaces at the bottoms of slots 18 in the chaser holders for a closing and thrust engaging action during thread cutting operations, and the keys and keyway arrangement at the sides of the slots and prongs for outwardly retracting the chaser holders and chasers provides for a very compact construction which permits a more accurate machining of parts operated upon.

60 A spring 43 is seated in a socket 42 in the closing ring 20 and acts against a pin 44 to force this pin against an annular surface 45 on the locking ring 27 to rotate the locking ring 27 into locked position when the abutments 28 are withdrawn from the sockets 41. The action of springs 43 and pins 44 against angular surface 45 on locking ring 27 also prevents locking ring 27 from moving forward in relation to the adjusting ring 26 when head closing action takes place. The locking ring 27 is limited in its rotation by means of a key 46 positioned in a rectangular groove 49 in the locking ring 27 which key engages a side 47 of a recess 48 in the operating ring 31.

5 The operation of the die head is as follows. With the parts in the position shown in Figure 8 the die head is in closed or threading position in which position the abutment 28 on the locking ring engages the face of abutment 29 on the closing ring to hold the closing ring in its forward position against the tension of spring 23. The thread cutting elements are in their innermost radial or threading position. When thread of a predetermined length has been cut the operating ring 31 is moved rearwardly of the body member by any suitable mechanism, not shown. Such mechanism may engage the annular groove 52 of this ring. As the operating ring 31 is moved toward the rear the pin 32 engaging the spiral slot 30 in the locking ring rotates this ring to permit the abutments 28 to drop into sockets 41 thus permitting springs 23 to force the closing ring 20 rearwardly of the body member. As the closing ring is withdrawn the prongs 17 by means of the grooves and ridges 34 and 35 move the chaser holders radially outward of the die head to withdraw the chasers from cutting position. The die head is then in open or non-threading position. To restore the die head to the threading position operating ring 31 is moved forward of the body member by any suitable mechanism, not shown, and this operating ring contacts the closing ring at surface 40 and forces the closing ring forwardly of the body member. As soon as the closing ring has moved far enough forward to withdraw the abutment 28 from socket 41 the spring 43 urging pin 44 into engagement with the locking ring rotates it to bring the abutment 28 to an overlapping position in relation to abutment 29 on the closing ring. The closing ring is then locked in its forward position with the thread cutting elements in threading position. When in this position the thrust against the thread cutting chasers is delivered through the chaser holders, closing ring and locking ring against the locking nut 26, which insures a rigid support for the chasers and insures accurate threads.

45 It will be obvious to those skilled in the art that various changes may be made in my device without departing from the spirit of the invention and therefore I do not limit myself to what is shown in the drawings and described in the specification, but only as indicated by the appended claims.

Having thus fully described my said invention, what I claim as new and desire to secure by Letters Patent, is:

1. A die head comprising a body member, a closing ring, an operating ring and a locking ring, adjustable means for holding said locking ring in axial position on the body member, and means between said closing ring and said locking ring for holding said locking ring against said adjustable means.
2. A die head comprising a body member, a closing ring, an operating ring, a locking ring and an adjusting ring, and resilient means between said closing ring and said locking ring for holding said locking ring against said adjusting ring.
3. A threading die head of the kind described having chaser holders and chasers mounted therein, said holders being operable to move the chasers into and out of threading position, a closing ring mounted on said body member having means engageable with said chaser holders for moving them radially upon axial movement of the closing ring, a locking ring mounted on said body member, an adjustable ring mounted on

said body member and serving as a reaction abutment to the locking ring, said closing and locking rings having mating abutments adapted to be rotated into abutting relation with each other to hold the closing ring in forward position, means 5 for moving said rings together upon displacement of said abutments to unmating position, a socket provided in one of said rings, a spring in said socket, a pin guided in said socket and projected by said spring into engagement with an inclined 10 surface on the other ring to yieldably impart a rotary movement between the rings, and to hold the locking ring against the adjusting ring, an operating ring mounted upon and supported only 15 by said closing and said locking rings, said operating ring being keyed to the closing ring and having means engageable with the locking ring for rotating this said locking ring against said yieldable force to permit collapsing of the thread 20 cutting elements.

4. A die head comprising a body, chasers on 25 said body and movable between closed operative positions and open inoperative positions, a closing ring movable axially along said body and arranged and designed to shift said chasers between the aforementioned positions, springs interposed between the closing ring and said body normally urging the chasers into inoperative positions, a locking ring sleeved upon said body 30 adapted to be rotated into and out of locking position, an adjustable abutment ring mounted upon said body in direct contact with said locking ring, an operating ring surrounding and in slidable engagement with the closing ring and the locking ring, said operating ring having means to 35 rotate the locking ring into and out of locking position upon axial movement thereof and means engageable with the closing ring to actuate the chasers into closed position, said body being provided with a peripheral skirt portion overlapping said operating ring.

5. A die head comprising a body member, a plurality of chaser holders slidably mounted on the body member, chasers mounted on said holders, a closing ring mounted on said body member and having means engageable with means 45 on the chaser holders for positively moving the chasers to non-threading position upon a rearward movement of said closing ring, a plurality of springs positioned to urge said closing ring to move the chasers to non-threading position, a locking ring, an adjustable locking nut on the body member engageable with the locking ring, an operating ring mounted directly upon said closing and said locking rings and having means 55 engageable with the locking ring for rotating said ring to a position to permit the closing ring to be moved axially of the body member by said springs to move the chasers to inoperative or non-threading position.

6. A threading die head comprising a body member having a plurality of slots in its forward end, a plurality of chaser holders mounted on said body member and having means engageable in said slots to hold them on the body member, a closing ring positioned about the body member and having projections engageable in slots in the said chaser holders for moving said holders to non-threading position upon a movement of said closing ring axially of the body member, a locking ring on said body member, means for holding said locking ring in fixed axial position on said body member, an operating ring mounted directly on said closing ring and said locking ring, means on said operating ring en-

gageable with said locking ring for rotating said locking ring to permit the closing ring to be moved axially of the body member to move the chaser holders to inoperative or non-threading position.

7. A threading die head of the kind described comprising a body, chasers carried by said body and movable between closed operative positions and open inoperative positions, a closing ring sleeved upon said body and adapted to shift said chasers upon axial movement thereof, a locking ring, said locking ring having abutments cooperating with abutments on the rear of the closing ring, a spring engageable with elements on said closing ring and on said locking ring and biased to cause relative rotary movement between said rings and an operating ring mounted on said closing ring and said locking ring and having a pin engageable with a spiral slot in said locking ring for rotating the locking ring upon axial movement of the operating ring, said operating ring being keyed to the closing ring to prevent rotary movement relative to the closing ring.

8. A threading die head of the character described comprising a body member having a head, chaser holders carried by said head, each chaser holder having a slot the bottom of which is inclined to the axis of the die head, said slot being open throughout its length in the peripheral surface of the chaser holder, and a closing member reciprocably mounted on said body and having members with cam surfaces for engaging the bottoms of the slots in the chaser holder for closing the die.

9. A threading die head of the character described comprising a body member having a head, chaser holders carried by said head, each chaser holder having a slot the bottom of which is inclined to the axis of the die head, said slot being open throughout its length in the peripheral surface of the chaser holder, a closing member reciprocably mounted on said body and having members with cam surfaces for engaging the bottoms of the slots in the chaser holder for closing the die, and cooperating means between said members having the cam surfaces and the slotted portions of the chaser holders for positively opening the die when the closure member is retracted.

10. A die head comprising a body member, a plurality of chaser holders slidably mounted on the body member, tangential chasers mounted on said holders, a closing ring mounted on said body member having prongs engageable with said holders, each chaser holder having a slot the bottom of which is inclined to the axis of the die head, said slot having a raised projection on its side, said projection being parallel to the bottom of said slot, prongs on the closing ring having cam surfaces for engaging the bottoms of the slots in said holders for closing the die head and holding the chaser holders in closed operating position, and said prongs having keyways on the sides engageable with the projections or cam surfaces on the side of the slots in said holders for positively moving the chasers to nonthreading position upon a rearward movement of said closing ring.

11. A threading die head comprising a body member having a flanged head provided with slots therethrough, chaser holders movably mounted on said flanged head, each of said chaser holders being provided with a slot terminating outwardly in its peripheral surface, the bottom of each slot being inclined to the axis of the

die head, a closing member reciprocably mounted in said die head, and provided with extensions projecting through the slots in the flanged portion of the body member and having cam surfaces engaging the bottom of the slots in chaser holders whereby the die is closed upon advancement of the closing member, said projections on the closing member and said chaser holder having key and keyway means parallel to the bottom 10 of the slot in the chaser holders for positively opening the die upon retraction of the closing member.

12. A threading die head of the kind described comprising a body, chasers carried by said body 15 and movable between closed operative positions and open inoperative positions, a closing ring sleeved upon said body and adapted to shift said chasers upon axial movement thereof, a locking ring, said locking ring having abutments cooperating with abutments on the rear of the closing ring, a spring engageable with elements on said closing ring and on said locking ring and biased to cause relative rotary movement between said rings and an operating ring slidably mounted 25 on said closing ring and said locking ring and having a pin engageable with a spiral slot in said locking ring for rotating the locking ring upon axial movement of the operating ring, said operating ring being keyed to the closing ring 30 to prevent rotary movement relative to the closing ring, and means for adjusting and securing said locking ring in fixed axial position on the said body member to determine the extent of opening of the thread cutting elements both in 35 threading and in non-threading position.

13. A threading die head of the kind described comprising a body member having a flanged head, a plurality of radial grooves in said head adapted to receive corresponding tongues on chaser holders and a plurality of slots through said flanged head and intersecting said grooves, a closing ring having forwardly extending cam elements which pass through said slots and slide along cam surfaces in the said chaser holders, means also on 40 the said cam elements cooperating with means on the said chaser holders for moving the chaser holders to non-threading position upon a retractive movement of said closing ring axially of said body member, a plurality of springs positioned between said closing ring and the flange 45 on the said head for urging the closing ring to move the chaser holders to non-threading position, a locking ring, an adjusting means, means for urging said locking ring against said adjusting means, means on the locking ring engageable with the closing ring for holding the latter in thread cutting position, an operating ring mounted on said closing ring and said locking ring, and means for causing relative rotary movement 50 between the operating and the locking rings when the operating ring is moved axially of the body member, and means for causing reverse relative rotary movement when the operating ring is moved axially in the other direction on the body member.

14. A threading die head comprising a body member having a plurality of radially movable chaser holders mounted thereon, tangential chasers mounted on the holders, a closing ring mounted 55 on said body member and having means engageable with said chaser holders to move them radially when said ring is moved axially of the body member, a spring engageable with said ring to move it in a direction to move the chaser 60 holders to open position, a locking ring adjust-

able axially of the body member for holding the closing ring in axial position on the body member and for determining its axial position thereon, a plurality of spiral slots in said locking ring, an operating ring mounted on said closing ring and said locking ring and having pins engageable in said slots, said operating ring being keyed to said closing ring to prevent rotation relative thereto, abutments on said locking ring cooperating with abutments on the closing ring for holding the latter in forward and threading position, movement of the operating ring axially of the body member causing rotation of the locking ring to cause the said abutments to become disengaged to permit axial rearward movement of said closing ring to move the chasers to non-threading position.

15. A die head comprising a body member, a closing ring, a locking ring, an operating ring mounted on the closing ring and on the locking ring, an adjusting ring and chaser holders, said chaser holders being movably mounted on the face of the body member, the closing ring having prongs in angular slots in the chaser holders to move the chaser holders away from and toward the axis of the body member, means to lock said holders in a fixed position in relation to the body member, means to change the fixed position of the chaser holders to different positions in relation to the body member, means to move the closing ring axially relative to the body member, means to lock said closing ring in fixed position, means to rotate the locking ring to locked and unlocked position, and means urging rotation of the locking ring and holding it 35 against the adjusting ring.

16. A die head comprising a body member, chaser holders and chasers radially movable on said body member, a closing ring axially movable on said body member and cooperatively engaging the chaser holders for moving the chasers radially in and out, and means cooperating with said closing ring in moving the chaser holders in and out on said body member including an adjusting member operable to adjust the threading size to the required diameter and also to move the chaser holders in and out for threading different diametrical sizes of work with the same chasers.

17. A die head comprising a body member, a closing ring, an operating ring, a locking ring and an adjusting ring, and resilient means between said closing ring and said locking ring for holding said locking ring against said adjusting ring and urging rotation of said locking ring.

18. A die head comprising a body member, a closing ring, an operating ring and a locking ring, adjustable means for holding said locking ring in axial position on the body member, and means between said closing ring and said locking ring for holding said locking ring against said adjustable means, and comprising a cam surface on one of the rings and a spring pressed element on the other ring.

19. A die head having prong receiving openings with outer surfaces parallel to the axis of the die head, chaser holders on said head, a closing ring having prongs for engaging and moving said chaser holders radially to open and close the die, said prongs having outer surfaces complementary to the outer surfaces of the prong receiving openings and substantially parallel to the axis of the die and having their inner surfaces diverging outwardly from the base of the prong.

20. A die head having prong receiving openings with outer surfaces parallel to the axis of the die head, chaser holders on said head, a closing ring having prongs for engaging and moving said chaser holders radially of the die head to open and close the die, said prongs having outer surfaces complementary to the outer surfaces of the prong receiving openings and substantially parallel to the axis of the die head 10 and having their inner surfaces diverging outwardly from the base of the prongs, and means between said outer and inner surfaces of the prongs for coacting with and engaging the chaser holders and producing an inward radial movement of the same upon an axial movement of the closing ring.

21. A die head comprising a body member, chaser holders and chasers radially movable on said body member, a closing ring axially movable on said body member and cooperatively engaging the chaser holders for moving the chasers radially in and out, and means cooperating with said closing ring in moving the chaser holders in and out on said body member including a 25 locking ring cooperating with said closing ring and rotatable to move the chasers radially to threading and non-threading positions, an operating ring axially movable on said closing and locking rings and cooperating to effect rotary 30 movements of the locking ring by axial movements thereof with respect to said locking ring, and an adjusting member engaging said locking ring and operable to adjust the threading size to the required diameter and also to move 35 the chaser holders in and out for threading different diametrical sizes of work with the same chasers.

22. A die head comprising a body member, chaser holders and chasers movable on said body 40 member, said chaser holders having angular slots, a closing ring having prongs engaging in said angular slots in the chaser holders to move them radially away from and toward the axis of the body member by axial movements of the 45 closing ring, and means cooperating with said closing ring in moving the chaser holders in and out on said body member including a locking ring cooperating with said closing ring and rotatable to effect the radial movement of the chasers to 50 threading and non-threading positions, an operating ring cooperating with said locking ring to effect rotary movements of the locking ring to locked and unlocked positions, an adjusting ring operable to change the fixed position of the 55 chaser holders to different positions in relation to the body member for adjusting the thread size to the required diameter and also to move the chaser holders in and out for threading different diametrical sizes of work with the same chasers, and means urging rotation of the locking ring and holding it against the adjusting ring.

23. A threading die head of the kind described comprising a body, chaser holders carried by said body and movable between closed operative 60 positions and open inoperative positions, tangential chasers carried by said holders, a closing ring sleeved upon said body and adapted to shift said chaser holders and chasers upon axial movement thereof, a locking ring, said locking ring having abutments cooperating with abutments 65 on the rear of the closing ring, a spring engageable with elements on said closing ring and on said locking ring and biased to cause relative rotary movement between said rings and an operating ring mounted on said closing ring and

said locking ring and having a pin engageable with a spiral slot in said locking ring for rotating the locking ring upon axial movement of the operating ring, said operating ring being keyed to the closing ring to prevent rotary movement 5

24. A die head comprising a body member, a closing ring, a locking ring, an operating ring mounted on the closing ring and on the locking ring, an adjusting ring and chaser holders, tangential chasers carried by said chaser holders, said chaser holders being movably mounted on the face of the body member to position the chasers in and out of thread cutting position, the closing ring having prongs in angular slots in the chaser holders to move the chaser holders and chasers away from and toward the axis of the body member, means to lock said holders and chasers in a fixed position in relation to the body member, means to change the fixed position of the chaser holders and chasers to different positions in relation to the body member, means to move the closing ring axially relative to the body member, means to lock said closing ring in fixed position, means to rotate the locking ring to locked and unlocked position, and means urging rotation of the locking ring and holding it against the adjusting ring.

25. A die head comprising a body member, chaser holders mounted on said body member, tangential chasers mounted on said holders, a closing ring cooperating with said chaser holders, an operating ring, a locking ring and an adjusting ring, and resilient means between said closing ring and said locking ring for holding said locking ring against said adjusting ring and urging rotation of said locking ring.

26. A die head comprising a body member, chaser holders mounted on said body member, tangential chasers mounted on said holders, a closing ring cooperating with said chaser holders, springs between the body member and closing ring operating to retract the chaser holders and chasers to an outer non-thread cutting position, an operating ring operable to position the chaser holders and chasers to threading and non-threading position, a locking ring, adjustable means for holding said locking ring in axial position on the body member, and means between said closing ring and said locking ring for holding said locking ring against said adjustable means and comprising a cam surface on one of the rings and a spring pressed element on the other ring.

27. A thread cutting head designed to carry chaser holders at one end and having a rearwardly extending cylindrical surface, a closing ring slidably axially of said head and having prongs projecting longitudinally to receive the chaser holders, an axially shiftable operating ring for actuating said closing ring, said operating ring having a portion provided with a cylindrical surface in close sealing and constantly overlapping relation to said first cylindrical surface, and spring means housed within the overlapped sealed portions of the closing and operating rings, and arranged to constantly tend to separate said closing ring and said mounting head axially.

28. A die head comprising a body member having a rearwardly extending cylindrical surface, chaser holders movably mounted forwardly on said body member, a closing ring having prongs projecting longitudinally of said body member to engage said chaser holders for moving them to

threading and non-threading positions by movements of the closing ring axially of the die head, and an operating ring also movable axially of the die head for actuating said closing ring, said operating ring normally closely engaging the outer surface of the closing ring and having a portion provided with a cylindrical surface in close sealing and constantly overlapping relation with said cylindrical surface of the body member thereby 5 providing a chamber in the die head structure, and means housed in said chamber tending to urge said closure member to chaser-retracting 10 position.

29. A die head comprising a body member, a 15 plurality of chaser holders mounted for radial

sliding movement on the body member, chasers carried by said holders, a closing ring mounted for axial movement on said body member and having outwardly projecting prong-shaped cam members each provided with a tapered cam surface for engagement with a corresponding surface on a chaser holder, each of said cam members and said chaser holders being provided with interengaging keys and keyways parallel to said tapered cam surfaces whereby when the closing 10 ring is moved axially rearwardly the chaser holders are positively retracted to non-threading position.

CHARLES A. REIMSCHISSEL.
